GUSTAVE CONSTANT DROUOT, OF PARIS, FRANCE, ASSIGNOR TO SOCIETE BRUNSWICK-BALKE-COLLENDER COMPANY, OF CHICAGO, ILLINOIS, A CORPORATION.

BILLIARD-TABLE.

1,158,793.

Specification of Letters Patent.

Patented Nov. 2, 1915.

Application filed September 21, 1911. Serial No. 650,521.

To all whom it may concern:

Be it known that I, GUSTAVE CONSTANT DROUOT, 19 Rue de la Pépinière, Paris, France, general manager, a citizen of the Republic of France, have invented a new Billiard-Table, of which the following is a full, clear, and exact description.

This invention relates to improvements in billiard tables and particularly relates to 10 an improved construction for mounting and securing the rails of a billiard table in which there is employed a slate bed.

Because of cheapness of material and economy of manufacture and various other 15 reasons, billiard tables as now generally constructed employ as a playing surface beds of slate. The use of such material, while it is considered as the best for the purpose, is open to several objections. As now generally constructed, the rails of the table are secured to the slate bed by bolts passing through the rails and into the bed horizontally, the rails being positioned outside of and against the outer edges of the bed. 20 Beds of this material with the rails thus supported are noisy, because of the resounding of the rails caused by vibration due to the impact of the balls. It is very difficult to so secure the rails to beds of this material 25 because of the characteristics of slate, which is very apt to split under the pressure of the bolts used for securing the rails in position. Further, this construction results in the disadvantage that the entire weight of the 30 rails rests on the bolts, which tends to bend and loosen them. Because of the tendency of slate to separate or split into slabs it is almost impossible to firmly tighten the bolts without risking splitting the bed, with the 35 result that the bolts never being very tightly fastened, easily loosen. Further, it happens in such constructions that the rails have a tendency to curve lengthwise, and the bolts being placed so low are not properly positioned to counteract this tendency, which is especially marked when the bolts are loosened. Furthermore, with such constructions the players are very apt to bend or break off, or, at least, loosen, the rails, which have 40 no support except the bolts, by sitting on the edge of the table. Constructions have been proposed which obviate some of these disadvantages. For instance, it has been 45 proposed to employ a vertical bolt passing through the slate and into the cushion strip

which supports the cushion. In such constructions, however, the members which constitute the rails are set square against the end of the slate bed. Such constructions, in addition to being noisy, are, for the reasons 60 heretofore pointed out, weak, and are objectionable for this and other reasons.

It is an object of the present invention to provide a rail construction in which the rail and the cushion strip and cushion rest directly on the upper face of the slate bed, the rail being of sufficient dimensions to provide a firm bearing and the rail being secured in position by a suitable number of bolts passing through the slate bed and the support 70 for the bed, there being provided anchoring means for firmly anchoring the bolts. In constructions embodying the invention the rail is positioned on the surface of the bed so that the outer edge of the rail is substantially flush with the outer edge of the bed, 75 an ornamental facing strip and top strip or rail covering the same and giving a finished appearance to the table, being employed.

For a better understanding of the invention, a detailed description of the same will now be given in connection with the accompanying drawings forming a part of this specification, it being understood that the description is of one of a set of four rails, 80 85 the construction of all the rails being similar.

Referring now to the drawings: Figure 1 is a section of a portion of the edge of a billiard table employing a slate bed and 90 bed supporting frame, showing the improved rail construction and one means for positioning the same on the bed. Fig. 2 is a top view of part of the construction shown in Fig. 1; Fig. 3 is a view showing in detail a preferred form of bolt used in the construction illustrated in Figs. 1 and 2; Figs. 4 and 5 are views similar to Figs. 1 and 2, showing a modified construction for anchoring the rail bolts and a somewhat different form of bolt; Figs. 6 and 7 are views similar to Figs. 1 and 2, showing a further modification of devices which may be employed for anchoring the bolts; Figs. 8 and 9 are views similar to Figs. 1 and 2, showing 95 100 105 a modified form of cushion rail and a modification of the devices employed for anchoring the bolts.

Referring now to the drawings, and first to Figs. 1, 2 and 3, the bed of the table is 110

2
formed of a slate slab *a* of suitable dimensions. This slab is, in the preferred construction, supported on a slate supporting frame *c*, which may be, if desired, of wood, 5 and carried on suitable standards which are not shown as they are unnecessary for an understanding of the invention. Mounted on the slate bed is the cushion rail *b*, which, in the construction illustrated in Figs. 1 to 10 7, is of wood. This rail is of sufficient width to afford a firm bearing on the bed and to receive the fastening devices heretofore referred to. This rail is mounted on the bed so that its outer edge is flush or substantially flush with the outer edge of the bed, 15 so that it is entirely supported by the bed and the strains are taken up by the bed. Secured to the inner edge of the cushion rail *b* is the smaller cushion strip *f* which 20 may be of rubber or of any other suitable desired material. The strip *f* is removably secured to the rail by glue or in any other desired manner, for instance, by the screws 2 shown in Fig. 8. The cushion *h* is secured to this cushion strip *f* in any suitable manner, as by gluing. It will thus be seen that in this construction the whole weight 25 of the cushion rail, cushion strip and cushion, which form the rail structure, is carried directly on the bed and any strains on these parts are borne directly by the bed. The cushion rails are secured in position on the bed by a suitable number of bolts *v* which pass up through the bed, bed-support 30 and the rail, and are provided with anchoring devices into which the bolts are screwed. These anchoring devices may be widely varied in construction.

In Figs. 1 and 2 is shown a convenient 40 construction in which there is provided a metallic anchor bar *x* which extends horizontally of the rail, one of these bars being provided for each of the rails. This bar sets into the rail, as shown in Fig. 1, and it 45 may be further secured, if desired, by screws 1 shown in Fig. 2, passing through the top rail *d*, which is provided for finishing off the rail structure on the top. The metal bar *x* has, at suitable intervals, threaded 50 apertures into which are screwed the threaded ends of the bolts *v*, the bolts when this construction is used being provided with a shoulder *v'* and a hole *t* which may be employed for setting up the bolts. When the 55 construction shown in Figs. 1 and 2 is employed the parts *d*, *x*, *b*, *f* and *h* are assembled together and the bolts *v* turned in to the metal bars. They are then dropped through suitable slots or holes in the bed *a* and bed 60 support *c* are set up by nuts *y* and washers *r*, by means of which the whole rail structure can be firmly clamped to the bed without risk of splitting it. After the bolts are 65 screwed up and the rail structure firmly clamped in place, an ornamental facing strip

e may be placed against the outer edge of the rail and bed support and may be secured in position by screws *z* taking into the bed support.

In the construction illustrated in Figs. 4 70 and 5 the metal anchor bar *x* is replaced by threaded nuts *x'* which are set into the rail *b* below the rail top *d*, these nuts being placed at suitable intervals along the rail. In this construction the bolts shown in Fig. 4 75 3 may be employed or a plain bolt may be employed, such as shown in Fig. 4. In assembling the construction shown in Figs. 4 and 5, the bolts *v'* with interposed washer *r* are screwed into the nuts *x'* from below. 80

In Figs. 6 and 7 a further modification of the anchoring devices is shown. In this construction threaded nuts *x''* are employed which are slipped through suitable apertures or slides *i* cut into the side of the rail *b* and the bolts *v''* are interposed from beneath the slate support *c* and the nuts *x''* screwed up through the aperture *i* after which the facing *e* is put in place. 85

In Figs. 8 and 9 a modified construction 90 of the rail is shown consisting of a hollow metallic bar of U shape in cross section and marked *b'*, this construction giving great rigidity and being desirable in some instances. In this construction the anchoring devices are similar to those shown in Figs. 6 and 7, the nut *x* being screwed on the bolt *v* through the open end of the rail *b'*, the ornamental strip *e* being placed in position after the bolt is set up. 95

With the construction so far described in addition to obtaining strength and rigidity a very considerable diminution of noise is obtained. If desired, a still further diminution of noise, and a practically noiseless construction can be produced by placing between the rail *b*, cushion strip *f*, and slate *a*, a thin strip of felt, oil cloth, or other sound insulating material *g*. The construction described, in which the rail rests directly on the slate slab, permits of the insertion of this strip of felt and provides a very desirable feature of construction. 100

With the construction so far described the whole rail structure is supported directly on the bed of the table; danger of splitting the bed is avoided by the use of the bolts passing upward through the slate and slate support, and the bolts may be set up as tightly as desired, thus securing a perfect fit to the table and preventing the tendency of the rails to warp horizontally; as the weight of the rails rests directly on the table, there is no bearing strain on the bolts, which consequently do not become bent or easily loosened; the correct angle which is so important to keep perfect is easily maintained on account of the great firmness of the rails. 115

It will be understood that the rails may be of somewhat different form than as 120 125 130

shown, and the anchoring devices shown may be varied somewhat in their details. The invention is therefore not to be limited to the exact construction shown but may be varied to include constructions which will be within the scope of the invention and the claims hereunto appended.

What is claimed is:—

1. In a billiard table the combination with a slate supporting frame, of a slate bed resting thereon, a set of cushion rails, removable cushion strips secured to the inner edges of the rails, cushions secured to the strips, said rails and strips being supported on the slate bed and having a bearing thereon, and the outer edges of the cushion rails being substantially flush with the outer edge of the slate bed whereby strains on the cushion rails are borne by the bed, bolts passing upward through the slate and slate bed, and accessible from the exterior of the table and anchoring means for the bolts carried by the rails into which means the bolts are screwed.
2. In a billiard table the combination with

a slate supporting frame, of a slate bed resting thereon, a set of cushion rails, removable cushion strips secured to the inner edges of the rails, cushions secured to the strips, a thickness of sound insulating material between the rails, the cushion strips and the slate, said rails and strips being supported on the slate bed and having a bearing thereon, and the outer edges of the rails being substantially flush with the outer edge of the slate bed whereby strains on the cushion rails are borne by the bed, bolts passing upward through the slate and slate bed, and accessible from the exterior of the table and anchoring means for the bolts carried by the rails into which means the bolts are screwed.

In testimony whereof I have signed my name to this specification, in the presence of two subscribing witnesses.

GUSTAVE CONSTANT DROUOT.
